US00D970874S

(12) **United States Design Patent** (10) **Patent No.:** **US D970,874 S**
(45) **Date of Patent:** **** Nov. 29, 2022**

(54) **AGLET**

(71) Applicants: **Butterfly Hedge LLC**, Seattle, WA (US); **Avi Geiger**, Seattle, WA (US)

(72) Inventors: **Avi Geiger**, Seattle, WA (US); **Jared Randall**, Seattle, WA (US)

(73) Assignees: **Butterfly Hedge LLC**, Seattle, WA (US); **Avi Geiger**, Seattle, WA (US)

(**) Term: **15 Years**

(21) Appl. No.: **29/727,943**

(22) Filed: **Mar. 13, 2020**

(51) LOC (13) Cl. **02-07**

(52) U.S. Cl.

USPC **D2/978**; D2/946

(58) **Field of Classification Search**

USPC D2/896, 910, 911, 913, 916, 925, 943, D2/946, 978; D21/672, 798; D26/37; D11/41, 79; D6/403, 406

CLAIM

The ornamental design for an aglet, as shown and described.

DESCRIPTION

FIG. 1 is a rear, top, left perspective view of an aglet in accordance with our new design;

FIG. 2 is a front, bottom, right perspective view thereof;

FIG. 3 is a front elevation view thereof;
FIG. 4 is a rear elevation view thereof;
FIG. 5 is a top plan view thereof;
FIG. 6 is a bottom plan view thereof;
FIG. 7 is a left elevation view thereof;
FIG. 8 is a right elevation view thereof;
FIG. 9 is a front, bottom, right perspective view of a portion
of an aglet in accordance with another embodiment of our
new design;
FIG. 10 is a rear, top, right perspective view thereof;
FIG. 11 is a front elevation view thereof;
FIG. 12 is a rear elevation view thereof;
FIG. 13 is a bottom plan view thereof;
FIG. 14 is a top plan view thereof;
FIG. 15 is a left elevation view thereof;
FIG. 16 is a right elevation view thereof;
FIG. 17 is a front, bottom, right perspective view of a portion
of an aglet in accordance with another embodiment of our
new design;
FIG. 18 is a rear, top, right perspective view thereof;
FIG. 19 is a front elevation view thereof;
FIG. 20 is a rear elevation view thereof;
FIG. 21 is a bottom plan view thereof;
FIG. 22 is a top plan view thereof;
FIG. 23 is a left elevation view thereof; and,
FIG. 24 is a right elevation view thereof.
